WELL MEASURING

Kenneth Bolton, Pittsburgh, Pa., and John E. Weiler, Duncan, Okla., assignors to Halliburton Oil Well Cementing Company, Duncan, Okla.

Application January 7, 1938, Serial No. 183,758

8 Claims. (CL 33—126.5)

This invention relates to apparatus for measuring the depth of oil wells or the like and more particularly to apparatus for automatically controlling the unreeling of a measuring line from a drum in response to movement of the line into an oil well.

Apparatus for measuring the depth of a well or for determining the position of an object moving in an oil well is well known. An example 10 of apparatus suitable for this purpose is found in the United States patent to Halliburton 1,692,037 granted November 20, 1928, for "Well sounding device".

It is a particular object of the present invention to devise improvements in apparatus of the type referred to in the above-mentioned patent and in which movement of the line into the well will be automatically controlled or governed.

It is a further object of the invention to provide automatic means for measuring the movement of a plug or other object traveling downwardly into an oil well, which plug may be for example of the type used in the cementing of oil wells, as shown and described in United States 25 patent to Halliburton 1,369,891, granted March 1, 1928, for "Method and means for cementing oil wells".

It is still another object of the invention to provide automatic means for controlling the unreeling of a flexible member from a reel or drum upon which it is wound.

Other objects and advantages reside in certain novel features of the arrangement and construction of parts as will be more apparent from 35 a consideration of the following description taken in connection with the accompanying drawings, in which:

Figure 1 is a somewhat diagrammatic representation of an oil well having apparatus constructed in accordance with one embodiment of the invention associated therewith, a portion of the well being shown in cross-section;

Figure 2 is a plan view, partly cut away, of the reel and control means shown in Figure 1;

Figure 3 is a somewhat diagrammatic representation of an oil well with another embodiment of the invention shown in connection therewith, a portion of the well being shown in cross-section;

Figure 4 is a plan view of the reel and control means employed in the arrangement of Figure 3; and

Figure 5 is an enlarged view of a portion of the apparatus shown in Figures 3 and 4, part of

the apparatus being cut away to show the internal construction.

In cementing an oil well it is common practice to keep track of the movement of a plug which follows a quantity of fluid cement as it is being pumped into the well, apparatus for this purpose consisting of a measuring line having a weight connected to its lower end and which weight follows the plug. The line is spooled upon a reel and controlled by a hand-operated brake. The operator releases the brake to permit the line and weight to move until the weight strikes the plug, this being determined by feeling of the line. Such measuring apparatus has gone into extensive commercial use. However, the operating of the line is tedious and not always accurate, especially in very deep wells, or where the wells are not straight.

In accordance with the present invention it is proposed to provide apparatus which will enable the operator to determine the position of a cementing plug without feeling of the line and without manually controlling the brake on the reel. Although the apparatus is thus primarily designed for use in connection with the cementing of an oil well, it will be obvious to those skilled in the art that the arrangement may be used for purposes other than cementing operations and wherever it is desirable to measure the position of an object in a well or to determine the depth of a well.

Referring to the drawings in detail, and first to the embodiment of the invention shown in Figures 1 and 2, it will be seen that an oil well is there illustrated as consisting of a bore hole 35 11 provided with a casing 12 which for purpose of illustrating the invention may be regarded as about to be cemented in the well. Within the casing 12 is located a cementing plug 13 which may consist of a wooden body provided with a 40 rubber cup 14 at its upper end. The plug 13 differs from those commonly employed heretofore in that it is provided with means for latching it to a measuring line 15 which extends upwardly through the casing 12 and out through a stuffing 45 box 16 on the casing head 17.

The latching means referred to above may consist of a pair of members 18 pivoted to each other at the top and connected to the measuring line 15. The lower ends of the members 18 project laterally as illustrated and are normally urged outwardly under the influence of a small coil spring 19. Integral with the plug 13 is a latch receiving member 20 which may consist merely of a cylindrical member having an inwardly ex- 55

tending flange adapted to overlie the laterally projecting portions of the latch members 18.

Located within the casing head, and held by means of a manually operable pin 21, is a go-devil 22, this member having the measuring line threaded therethrough. When it is desired to release the measuring line from the plug 13 the pin 21 may be pulled, allowing the go-devil 22 to travel downwardly and strike the latch members 18. The lower portion of the go-devil 22 is provided with a conical recess 23 so as to enable it to readily collapse the latch members 18 and release the same from the plug upon the go-devil striking these members.

15 The upper end of the casing 12 beneath the casing head 17 is shown provided with a laterally extending pipe 24 through which mud or other fluid may be pumped in forcing the body of fluid cement upon which the plug 13 is presumed to 20 rest downwardly into the well. It will readily be seen that as long as the latch members 18 are connected to the plug 13, movement of the plug downwardly will pull the measuring line 15 with it into the well.

25 The casing head 17, in addition to being provided with a stuffing box 16 mentioned above, is provided with a staff 25 on which a pulley 26 is mounted, the measuring line 15 extending over this pulley and from there to a reel 27 which has 30 associated with it a measuring device and an automatic brake, which will now be described.

The reel 27 may be mounted on a suitable means, such as the post 28, by means of a shaft 29. In order to determine how much line has 35 been fed into the well, a measuring device is provided. This device per se may be identical with that shown and described in the Halliburton Patent 1,692,037 mentioned above. It consists of a measuring wheel 30 around which the measuring line passes, the wheel 30 being supported on suitable arms 31 which are maintained in an approximate balance by means of the weight 32. Between the measuring wheel 30 and the reel 27, a brake control pulley 33 is provided, this pulley 40 being mounted upon a shaft 34 in such a way that it can travel back and forth in front of the reel in parallel to the axis thereto as the line on the reel is spooled or unspooled. The shaft 34 is carried by two lever arms 35, one on each side 45 of the reel, as shown in Figure 2. These lever arms are pivotally mounted upon the shaft 29 and are connected by means of links 36 to brake bands 37 adapted to cooperate with a brake drum 38 integral with the flanges on the reel. The 50 lever arms 35 may be biased in such a direction as to normally cause the setting of the brakes by means of a weight or spring. In the arrangement illustrated, a weight 39, together with associated link and lever mechanism, is shown for 55 this purpose. The weight 39 may be adjustably mounted upon a lever 40, one end of which is connected to a fixed fulcrum 41. Near the fulcrum the lever 40 is connected by a link 42 to a bar 43 integral with the lever arms 35. The lever 60 mechanism 39 may exert such a bias upon the lever arms 35 as to prevent releasing of the brakes until a predetermined tension is placed upon the line. For example, if the entire measuring line suspended in the oil well would exert a tension, 65 in addition to its own weight, at the well head, of around 300 pounds, the weight 39 may be so adjusted as to prevent unwinding of the line from the reel until more than 300 pounds lifting force is exerted on the pulley 33. Thus, the arrangement 70 may be so adjusted that the line will never

unreel due to its own weight but can be moved only in response to movement of the cementing plug 13 or other device to which the line may be connected, such as would result when fluid is being pumped into the well above such a plug. 5

It is to be noted that the brake arrangement is such that when the initial tension referred to above, say 300 pounds, is overcome, any further increase in tension acts to release the brakes further and enable the reel to revolve faster and 10 the line to be unwound at a greater speed. On the other hand, the minute that the tension is lowered, the brakes tend to set and prevent further unreeling of the line. In this way the 15 operation of the line is rendered wholly automatic and no particular attention by the operator need be paid thereto.

It is within the purview of the invention to carry out the principles illustrated in Figures 1 and 2 in a variety of ways. One additional way 20 is by means of the apparatus illustrated in Figures 3, 4 and 5. Referring to these figures in detail, and first to Figure 3, it will be seen that a well identical with that illustrated in Figure 1 is there shown and the parts which correspond to the 25 arrangement of Figure 1 have been similarly designated.

The main difference in the apparatus of Figures 3, 4 and 5 from that of Figures 1 and 2 involves the particular mechanism for controlling the 30 operation of the reel upon which the measuring line 15 is wound. In Figures 3, 4 and 5 the reel is designated 44. It is mounted upon a shaft 45 which may be controlled by a brake operated by means of the hand lever 46, if desired. In addition to the hand-operated brake, a hydraulic 35 brake is associated with the reel 44. The hydraulic brake may be of a known form and comprising a small gear pump 47, the gears 48 in which are caused to rotate by being connected 40 through a suitable gear train to a gear wheel 49 integral with the reel. These features particularly are shown in detail in Figure 5.

The gear pump 48 is connected by means of suitable conduits 50 to a balanced control valve 45 the housing of which is shown at 51. The gear pump 47, the conduits 50 and the housing 51 for the control valve may be filled with oil or other fluid so that when the gears in the pump are rotated oil will be caused to flow in a circuit 50 through the conduits 50 and the housing 51 of the control valve. The arrangement may be such that the valves within the housing 51 may be closed, or so nearly closed as to create considerable resistance to movement of the fluid therethrough and thus operate as an effective brake upon the reel 44. As shown in Figure 5, the valves 52 within the housing 51 may be of the balanced type so that movement of fluid through the housing 51 will not tend to either seat or unseat the same. The valves 52 may be mounted upon a stem 53 and controlled by means of a spring 54 the tension in which may be adjustable as by means of the adjusting nut 55. The spring 54 bears upon a plate 53' integrally secured to the valve stem 53. The stem passes through suitable stuffing boxes 56 and 57 and terminates at its lower end in a piston 58 within a cylinder 59 connected by means of a flexible tubing 60 to a tension responsive device 61 carried by the frame 62 70 of the measuring apparatus.

As shown in Figures 3 and 4, the measuring apparatus is similar to that mentioned above in connection with Figures 1 and 2 and is also similar to that described in the Halliburton Patent 75

1,692,037 mentioned above, except that means is provided for causing a member thereon to move relative to the frame 62 in accordance with the tension in the line 15 as it passes through the 5 frame 62 from the reel 44 into the well.

Thus the measuring frame 62 is supported by means of arms 63 pivoted upon a shaft 64 connected to the post 65 upon which the reel 44 is mounted. One of the arms 63 may be provided 10 with a balancing weight 66 which may be adjusted if desired. The measuring wheel itself is shown at 67 and may be the same as that described in the Halliburton patent mentioned and provided with a suitable counter 68 for indicating how 15 much line is removed from the reel.

In addition to the measuring wheel 67, the frame 62 carries an idler pulley 69. Both the measuring wheel 67 and the idler pulley 69 may be provided with suitable rollers 70 which hold 20 the line in proper contact therewith.

Between the measuring wheel 67 and the idler pulley 69 a tension responsive wheel 71 is mounted. This wheel is connected through a suitable yoke 72 to a piston rod 73 which carries a suitable piston 74 mounted within a cylinder 75 to which the flexible tubing 60 referred to above is connected.

It will thus be seen that the arrangement is such that the spring 54 in the control valve housing 51 (see Figure 5) transmits pressure through fluid within the cylinders 59 and 75 and the conduit 60 in such a way as to normally urge the piston 74 upwardly, thus tending to place a bend within the measuring line 15 at the point of contact of the tension responsive wheel 71. As the tension in the measuring line increases the line adjacent the wheel 71 tends to straighten out, causing the piston 74 to move downwardly and thus causing the valves 52 to open wider and 40 cause the load upon the gear pump 47 to diminish, thus permitting the reel 44 to rotate faster.

In addition to the parts mentioned above, a by-pass conduit 76 may be connected around the pump 47 and this by-pass is provided with a control valve 77. It is also preferable to provide a surge tank somewhere within the system, and such a tank is illustrated at 78.

Thus it will be seen that the operation of the arrangement of Figures 3, 4 and 5 is similar to 50 that of the arrangement shown in Figures 1 and 2. If desired, the arrangement may be so adjusted that the valves 52 remain closed until a predetermined pressure is exerted upon the wheel 71. This may be accomplished by pre-loading 55 the spring 54 as by turning the nut 55 downwardly until a predetermined tension is placed therein which will have to be overcome before the valve stem 53 can move or by substituting a weight for the spring 54 or by otherwise suitably loading the 60 valve stem 53.

In both embodiments of the invention shown, the same means is illustrated for latching the measuring line to a cementing plug. It is within the purview of the invention to connect the line 65 to the plug by means other than that shown, although the apparatus is not primarily designed for use except where some means is provided for connecting the line to the plug. It is within the purview of the invention, however, to merely provide a connecting link between the lower end of 70 the line and the plug which would have a predetermined parting strength so that when it is desired to disconnect the line from the plug all that will be necessary will be to prevent the reel from rotating and exert pump pressure upon the plug 75

until this link parts. Various other devices could be used for connecting the measuring line to the plug.

While only two embodiments of the invention have been shown and described herein, it is obvious that various changes may be made in the construction and arrangement of parts without departing from the spirit of the invention or the scope of the annexed claims.

I claim:

1. Apparatus adapted for use in the cementing of an oil well or the like including a plug adapted to be pumped into the well with a batch of fluid cement, a measuring line connected to the plug, and automatic means for feeding the line into the well as the plug moves downwardly therein, said automatic means having a brake cooperating with the line and adapted, when set, to retard movement of the line and an arrangement for operating the brake to release the same when 20 the line is subjected to a predetermined tension due to pressure exerted on said plug.

2. Apparatus adapted for use in the cementing of an oil well or the like including a plug adapted to be pumped into the well with a batch 25 of fluid cement, a measuring line connected to the plug, and automatic means for feeding the line into the well as the plug moves downwardly therein, said automatic means including a brake, lever mechanism for setting or releasing the 30 brake, and an arrangement for holding the lever mechanism against movement and hold the brake in set position except when the plug is moving.

3. Apparatus adapted for use in the cementing of an oil well or the like including a plug 35 adapted to be pumped into the well with a batch of fluid cement, a measuring line connected to the plug, and automatic means for feeding the line into the well as the plug moves downwardly therein, said automatic means including a fluid 40 pump and means for controlling the resistance to movement of the pump in response to tension existing in said measuring line.

4. Apparatus adapted for use in measuring depth in an oil well or the like comprising, in 45 combination, a reel, a measuring line spooled thereon, a device for indicating the amount of line unspooled from the reel, a brake for controlling rotative movement of the reel and automatic mechanism for operating said brake, said 50 mechanism causing the brake to set when less than a predetermined tension exists in said measuring line and causing the brake to release when more than a predetermined tension exists in said measuring line.

5. Apparatus adapted for use in measuring depth in an oil well or the like comprising, in combination, a reel, a measuring line spooled thereon, a device for indicating the amount of line unspooled from the reel, a brake for controlling rotative movement of the reel and mechanism for operating said brake to set or release the same, said mechanism being operative automatically to diminish the setting pressure on the 65 brake in response to increased tension in the measuring line and automatically to increase the setting pressure on the brake in response to decreased tension in the measuring line.

6. Apparatus adapted for use in measuring depth in an oil well or the like comprising, in 70 combination, a reel, a measuring line spooled thereon, a device for indicating the amount of line unspooled from the reel, a brake for controlling rotative movement of the reel and mechanism for operating said brake, said mechanism 75

including a pulley engaging said line, a lever connected to said brake and pulley and means for holding said lever against movement until a predetermined tension is exerted in said measuring line.

5. 7. Apparatus adapted for use in measuring depth in an oil well or the like comprising, in combination, a reel, a measuring line spooled thereon, a device for indicating the amount of 10 line unspooled from the reel, a brake for controlling rotative movement of the reel and mechanism for operating said brake, said mechanism including a pump connected to said reel, a control valve, fluid conduits connecting said control 15 valve to said pump and an arrangement operable in response to variations in tension in said measuring line for controlling the position of said control valve.

8. Apparatus adapted for use in measuring depth in an oil well or the like comprising, in combination, a reel, a measuring line spooled thereon, a device for indicating the amount of line unspooled from the reel, a brake for controlling rotative movement of the reel and mechanism for operating said brake, said mechanism including a pump connected to said reel, a control valve, fluid conduits connecting said control valve to said pump and an arrangement operable in response to variations in tension in said measuring line for controlling the position of said control valve, said arrangement including a wheel and means for suspending the wheel for free movement with movement of said measuring line.
